THOMAS DE LA MARE, OF SALT LAKE CITY, UTAH

METHOD OF CONSTRUCTING AND MAINTAINING CRUDE OIL CONDUCTORS

Substitute for application Serial No. 165,449, filed February 2, 1927. This application filed May 29, 1930.
Serial No. 457,079.

This invention relates to an improved method of constructing crude oil conductors, and its principal objects are to provide conductors which shall:

- 5   First. Resist corrosion from the inside, and decay and corrosion from the outside;
  - Second. Have comparatively long life;
  - Third. Be especially adapted for use in the crude oil industry;
  - 10   Fourth. Be expeditiously manufactured in place;
  - Fifth. Be economical.
- In accomplishing these objects, I have evolved a method of constructing a composite pipe consisting of a wood center or lining surrounded by a jacket or shell made of concrete, in which the lining is specially treated. For the hollow center, ordinary steel-banded wood stave pipe may be used,

20   and the concrete jacket is preferably built around this pipe in the field.

Before jacketing, the wood pipe is treated in the following manner. After sealing substantially water-tight, both ends of a certain 25 length, say one mile, of pipe when placed in position, I fill the pipe with preferably a saturated solution of common salt, (NaCl and water). The filled pipe is then preferably subjected to a considerable pressure, say

30   about 100 lbs. per sq. inch, though any pressure above atmospheric pressure would give better results in use than if treated with the same solution at only atmospheric pressure. The proper pressure acts to thoroughly im-

35   pregnate the wood with the salt solution and also reveals any leakage which may exist. Small leaks are usually closed by the swelling of the wooden staves, and should there be any larger leaks, these may be plugged by

40   driving in wooden wedges or by other means.

After the wood is thoroughly soaked, and all 45   leaks have been stopped, the concrete jacket is applied in sections to the entire length of pipe, each section being about 10 ft. in length, and the sections being spaced a few inches apart so as to provide for the shrinkage of the concrete, which ordinarily takes about 20 days to "cure".

While the first length is curing, a second 50   length of the wood pipe, also about one mile

long, is placed closely following the first length, a distance of a few feet being left between the two ends. The brine from the first length can now be piped into the second length, and any additional quantity of brine necessary to fill the second length of pipe, be supplied thereto. After subjecting this length to the usual pressure, it also is jacketed with concrete, and the process repeated for the third length, and so on.

Impregnating the wood lining with a salt solution not only swells the wood until it is water tight in the beginning, but keeps it so due to the hygroscopic properties of the salt particles ensconced in the cellular structure 65 of the wood, which are always in readiness to draw on the moisture content of the crude oil to keep the impregnation of the wood at substantially the maximum degree.

The present method has been devised with 70 the particular advantage in view of keeping the salt solution saturated wood lining tight by causing to flow through it, crude oil having a salt solution content, by means of which the salt content of the wood lining is kept 75 up to maximum. This depends upon a certain policing action exercised by the salt particles in the crude oil to hold back the salt particles in the wood lining.

The concrete jacket is applied while the 80 salt solution is still contained within the wood lining, or very soon after, to insure against its cracking. If the wood lining were allowed to dry, and consequently shrink, before the concrete jacket was applied, the 85 subsequent swelling and expansion of the lining due to its absorption of the salt solution from the crude oil, would crack the concrete jacket.

The pressure to which the salt solution is 90 subjected, causes its thorough penetration into and around the fibers of the wood thereby intensifying the preservative action of the salt and also intensifying its action to keep the wood lining always tight.

The present application is a substitute for, and a continuation of, one filed by me February 2, 1927, Serial No. 165,449.

The features of this invention for which the protection of Letters Patent is desired,

are collectively grouped in the claims concluding this specification.

In the drawing, which is somewhat diagrammatic,

5 Fig. 1 represents lengths of the wood pipe, parts broken away, after having been put in place ready for pressure treatment with brine;

10 Fig. 2, the same, with forms ready for placing concrete;

Fig. 3, a cross section taken through the pipe shown in Fig. 1, enlarged;

15 Fig. 4, a cross section taken through the pipe shown in Fig. 2, enlarged, showing various form details located in the background, in elevation;

Fig. 5, a cross section taken through the completed pipe;

Fig. 6, a minor detail; and

20 Fig. 7, a fragmentary axial section showing a detail, drawn to the same scale used in Figs. 3 and 4.

Referring to the drawing, 20 indicates suitable lengths of wood stave pipe, 25 indicates the usual spirally wound steel bands, the staves having been assembled and banded in the usual manner. At the two ends of the said length are placed removable clamping bands preferably made of steel and consisting of the two sections 26 held together by bolts 27. After the staves are cinched together by the bands, wooden plugs 28 may be driven into the ends of the pipe, so as to make a watertight seal. In these plugs may be inserted the nipples 29, which together with the union 30 and the valve 31, provide means for transferring the brine from one length of pipe to the other.

These connections may be removed, and 40 others (not shown) inserted in any well known manner, for filling the lengths with brine from other sources.

When the wood pipe has been thoroughly tested and all leaks stopped as previously mentioned herein, concrete is placed in the trench 32 under the pipe. After this has been done, the forms consisting of planks 34, are put into position and held by means of stakes 35 on the outside thereof, while adjustable collars 36, made up of links 36-1 and 36-2, hold the planks apart from each other. The collars are placed at such distances apart as may be desired, say ten feet, to form shrinkable sections. Between the 55 sections are spaces 37 which may be only a few inches in length, and which, after the shrinkage sections are thoroughly cured, may be concreted over to form coupling bands between the section, as indicated at 38.

60 As a pipe may be considered a container, it will be obvious that this method of construction can be applied to a container of any type, such as a tank. Again, a tank may be considered nothing more than a section of 65 pipe set on end, such section being provided

with a bottom or with a top and bottom, as desired.

An important feature of this invention is to keep a salt (sodium chloride) impregnated wood pipe, and especially a pressure-impregnated wood pipe, tight, by conducting through said pipe crude oil or other liquid having a considerable salt content, said crude oil and salt content being in contact with the salt impregnated wood of said pipe, thereby preventing the salt initially deposited in the pores of the wood, from being absorbed or withdrawn, which would be the case were a liquid without salt content to be passed through the pipe. The salt content may be a natural constituent of the liquid or the liquid may be artificially charged with the salt content.

Having fully described my invention, 85 what I claim is:

1. The method of constructing a pipe line of composite material, said pipe line including successive lengths of wood pipe as a core, consisting in plugging the ends of said lengths, substantially filling each length with brine under a predetermined pressure, applying a jacket of concrete to each length while under said pressure, and coupling all said lengths together after said concrete is applied.

2. The method of constructing composite pipe having a wood lining and a concrete jacket surrounding said lining, consisting in closing the ends of said wood lining, substantially filling the space inside the lining with brine, subjecting said brine to a predetermined pressure before concrete is applied, allowing said lining to remain under said pressure until all parts thereof have swelled to the desired degree, and applying said concrete jacket while the said lining is under internal pressure.

3. The method of constructing a container for crude oil having NaCl in solution associated therewith, consisting in subjecting a pipe porous material to contact with a water solution of NaCl under pressure, and enclosing said pipe in plastic material while under said pressure.

4. The method of constructing, and maintaining tightness in, a salt impregnated wood pipe, consisting in subjecting said wood pipe to contact with a water solution of NaCl under pressure, enclosing said wood pipe in plastic material while under pressure, and conducting crude oil having a considerable salt content through said wood pipe, said crude oil with its salt content being in contact with the inner surface of said wood pipe.

In testimony whereof, I sign my name hereto.

THOMAS DE LA MARE.
